Primary Examiner—Bernard Ansher*Assistant Examiner*—M. Siegel*Attorney, Agent, or Firm*—Litman, McMahon & Brown[57] **CLAIM**

The ornamental design for a combined spray container and cap, as shown and described.

DESCRIPTION

FIG. 1, is a perspective view of a combined spray container and cap showing my new design;

FIG. 2 is a side elevational view thereof, the undisclosed front, rear and opposite side being identical;

FIG. 3 is a top plan view thereof;

FIG. 4 is a bottom plan view thereof;

FIG. 5 is a perspective view thereof, with the cap removed for clarity of illustration;

FIG. 6 is a top plan view of FIG. 5;

FIG. 7 is a front elevational view of FIG. 5;

FIG. 8 is a left side elevational view of FIG. 5, the undisclosed opposite side being a mirror image; and,

FIG. 9 is a rear elevational view of FIG. 5.
